HORACE S. CARLEY, OF CAMBRIDGEPORT, MASSACHUSETTS.

Letters Patent No. 68,485, dated September 3, 1867.

IMPROVEMENT IN BOTTLE-STOPPERS.

The Schedule referred to in these Letters Patent and making part of the same.

TO ALL WHOM IT MAY CONCERN:

Be it known that I, H. S. CARLEY, of Cambridgeport, in the county of Middlesex, and State of Massachusetts, have invented a new and improved Bottle-Stopper; and I do hereby declare that the following is a full, clear, and exact description thereof, which will enable others skilled in the art to make and use the same, reference being had to the accompanying drawings, forming a part of this specification, in which—

Figure 1 represents a sectional view of my invention.

Figure 2 is a side view of the same.

Similar letters of reference indicate corresponding parts.

The object of this invention is to provide a bottle-stopper for soda-water bottles and other bottles containing liquids charged with carbonic acid, which can be firmly closed and held down, which can be easily opened when desired, and which will always be attached to the bottle whether opened or closed.

The invention consists in securing to the stopper two or more wire rods, which project from the under side of the stopper, and are inserted into the bottle. The rods are spread apart by their own spring, so that their lower ends press against the inside of the neck of the bottle. At their lower ends they are bent out, so that they can catch under a shoulder formed on the inside of the bottle. The stopper is inserted by pressing the wires together. When it can be closed by any suitable apparatus; and when to be opened it can be drawn out until the hooks catch under the aforesaid shoulder. The stopper will thus be at all times retained on the bottle without preventing the same from being filled or emptied.

A represents a stopper, made of India rubber or other suitable material. From its under side project two or more wire rods B B, which may be attached in any suitable manner, although I prefer the manner illustrated in fig. 1. In this a plate, a, of sheet metal is placed upon the stopper, and is perforated with holes. The wire is passed through one hole in the cork and plate, is then bent upon the plate, and passed down again through the other hole in the plate and stopper. Thus two wire rods are obtained, which have sufficient spring to press their ends apart. The wire used can be made of any suitable metal, flat or round. At their ends these wire rods are slightly bent out, as shown in fig. 1. In the neck of the bottle, not far from its mouth, is formed a shoulder, b, as shown. The wires have to be pressed together when to be inserted in the bottle, and their ends are then by their own or another spring pressed against the sides of the neck of the bottle.

The liquid can be filled in in the ordinary manner, and the stopper forced down by the usual machinery. The stopper may be held down by means of a loop or clasp, C, which is hinged to a ring, D, laid around the neck of the bottle, as shown, or by any other suitable device. The ends of the wires B catch under the shoulder b, and prevent the cork from being withdrawn or lost when the bottle is opened. In fig. 1 the bottle is represented as being opened; and in fig. 2, and by red lines in fig. 1, it is represented as being closed.

Instead of being bent out at the ends, the wires may be provided with projecting stops attached to the same in any suitable manner.

One wire rod, when so bent as to form two stops at the lower end, as shown by dotted lines in fig. 2, will answer the purpose as well as the two rods B, and may be used with equal advantage.

I claim as new, and desire to secure by Letters Patent—

A bottle-stopper, consisting of the cork A, made of India rubber or other suitable material, and provided with one or more spring wires B B, which project downwards from the cork, and which are made and operating substantially as and for the purpose herein shown and described.

H. S. CARLEY.
